UNITED STATES PATENT OFFICE.

ROBERT O'TOOLE, OF BIRMINGHAM, ALABAMA.

DISPLAY-RACK.

1,212,245.

Specification of Letters Patent. Patented Jan. 16, 1917.

Application filed October 19, 1915. Serial No. 56,807.

To all whom it may concern:

Be it known that I, ROBERT O'TOOLE, a citizen of the United States of America, residing at Birmingham, in the county of 5 Jefferson and State of Alabama, have invented certain new and useful Improvements in Display-Racks, of which the following is a specification.

My invention relates to a display rack 10 adapted for ready attachment to and detachment from shelves for the display of merchandise.

My invention is particularly adapted for the display of shoes and the rack is designed with a view to making it attachable to the shelves without disturbing the normal arrangement of the shoe boxes thereon. I have found that a display rack of this character will be of especial advantage in 20 the retailing of shoes due to the fact that a customer can be served very much more readily and quickly if the various styles of shoes in the shelves can be conveniently displayed, thus enabling the customer to quickly select the pattern or style desired. It will also take advantage of the valuable 25 display space along the walls which is now wholly unused, due to the fact that shoe boxes are not designed or adapted to display their contents. I also consider that by designing the racks for attachment to the shelves without interfering with the shoe box arrangement thereon I will produce a more serviceable and satisfactory 30 method of attachment.

A further object of my invention is to so design the shelf engaging member of the rack that it will be braced laterally by the boxes on each side of it both above and below the shelf to which it is applied and held by them against swinging laterally or rocking sufficiently to permit the shoe to fall therefrom.

A further object of the invention is to 45 adapt the shelf engaging member of the rack not only to clamp the shelf but to take advantage of the weight of the shoe to increase the clamping action and thus make the rack steadier the greater the weight 50 thereon.

A further object of my invention relates to the novel method of forming the display rack from a bent wire and shaping it to form a very desirable display holder for 55 a shoe or other article.

My invention further comprises the novel

details of construction and arrangements of parts which are hereinafter more particularly described, and which in their preferred embodiment only are illustrated in 60 the accompanying drawings, and in which:—

Figure 1 illustrates a display rack in a side perspective view attached to a shelf. Fig. 2 is a front perspective view of Fig. 1.

Similar reference numerals refer to similar parts throughout the drawings.

In the form illustrated the display rack comprises a shelf engaging clamp portion formed of bent wire having a vertical loop 1 from which the wire strand leads forwardly to form the top member 2 of the clamp. The wire is then bent down at 3 and back at right angles rearwardly under the member 2 to form the bottom member 4 of a bend which opens inwardly to receive and clamp the shelf 9. The top member 2 is bent down to form with the member 4 a spring shelf clamp. At the rear end of member 4 the wire is bent down at right angles to form a vertical leg 5 and 75 forwardly to form a member 6 which extends along under member 4 to its outer end and its rack forming end 7 is then bent at an acute angle downwardly and twisted in the manner hereinafter described to form 80 the display rack proper. The members 4, 5 and 6 form a bottom bend which opens outwardly. A link 8 connects the forward ends of the members 4 and 6 and holds them together to apply the downward pressure 85 from the weight of the shoe on the outer ends of both clamp members 2 and 4. All the clamp or shelf engaging portion of the rack lies in the same vertical plane so that when forced over the shelf 9 the members 90 1, 2, 4 and 6 will form bends generally conforming in shape to a wide straight line letter S, and, being disposed vertically, they will fit between the shoe boxes 10 both above and below the shelf without abnormally 95 spacing or disarranging them and will be braced by them so as to prevent the lateral swinging or twisting of the rack.

The display portion of the rack is peculiarly designed for shoes and is formed 100 preferably in the following manner:—The wire 7 is bent upwardly to one side to form an arm 11 that is bent back on itself and then crosswise to form a horizontal instep support 12 and is then bent up and back 105 on itself and downwardly at 13 until it joins the base of the arm 11, where the wire

is given a complete turn about such base and thence is bent at an angle laterally to form a member 14 which at its end is bent up and then back down at 15 and then horizontally crosswise to form the sole support 16 and then up and back at 17 and finally leads at an angle to form the leg 18 and has its end twisted around the member 14 at the point 19. The vertical bends in the members 11 and 13 form upright stops 20 and 21 at each end of the instep support 12 and the bends 15 and 17 form upright stops at each end of the support 16 for the sole. The instep support 12 is raised sufficiently above member 7 to hold the heel of the shoe clear thereof when the sole of the shoe rests on the cross support 16. The members 11 and 13 are disposed angularly to each other and are tied together at the apex of the angle and the members 14 and 18 are similarly inclined and tied together. I thus obtain in simple form a very strong and effective display rack for shoes which will prevent the easy dislodgment of the shoe therefrom and which will hold it most conveniently and firmly for display purposes.

In operation, the clamp end of the rack has its upper bend forced over the shelf between the vertical rows of boxes, the members 2 and 4 receiving and clamping the shelf between them. When the shoe is placed on the rack its weight on the outer end of the rack will act through the loop 8 as a fulcrum to prize the rear end of the clamp member 4 upwardly against the bottom of the shelf and to apply a downward pull to the top clamp member 2 so that both clamp members are drawn more tightly against the shelf and increase the firmness of the attachment thereto of the rack. It will be noted that the shoe boxes on each side by engaging the loop members 1 and 6, will not only hold the rack against swinging horizontally but also against a tendency to turn on a horizontal axis through the center of the clamp.

Having thus described my invention, what I claim as new and desire to secure by Letters Patent, is:—

50 1. A display rack comprising a frame for supporting the article to be displayed, and a vertically disposed shelf engaging clamp connected to said frame and formed of wire bent in loops, all of which lie in the same vertical plane and at least one of which loops projects substantially out of the plane of the shelf to be received between and laterally braced by merchandise on the shelving.

60 2. A shoe display rack formed of bent wire and comprising a shoe supporting portion and a shelf engaging portion, the shoe supporting portion comprising means to engage and support a shoe for display, and said shelf engaging portion comprising a U-bend in the wire adapted to clamp over

the outer edge of the shelf, the inner end of the under member of the bend being bent back in the plane of the U-bend and connected at its outer end to the display frame and means to support said bent back member from the outer end of the U-bend which engages the shelf.

3. A shoe display rack formed of bent wire and comprising a shoe supporting portion and a shelf engaging portion, the shoe supporting portion comprising horizontal heel and sole supporting members having end stops to prevent the lateral displacement of the shoe, and said shelf engaging portion comprising wire bent like a wide letter S with its folds lying in a vertical plane at right angles to the shelf and with its top member adapted to engage the top face of the shelf and its bottom bend adapted to engage the bottom face of the shelf, the outer ends of the horizontal members of said bottom bend being connected together.

4. A shoe display rack formed of bent wire and comprising a display frame, and a shelf engaging clamp, said clamp being S-shaped in side elevation and adapted between the inner ends of its top and middle members to receive and clamp a shelf and having a link connecting the outer ends of its middle and bottom members, substantially as described.

5. A shoe display rack comprising a shoe supporting frame formed of bent wire and having integral therewith a shelf engaging member, said member being formed by bending the wire to form a substantial S-shape with its horizontal members elongated and lying substantially parallel and in the same vertical plane when in use, and means to support the outer end of the bottom member from the shelf, when the latter is in position between the two upper members.

6. A shoe display rack formed of bent wire and comprising a shelf engaging member formed by making a reverse bend in the wire in the same plane to form an inwardly opening top bend and an outwardly opening bottom bend, a link connection joining the wire at the outer end of the outwardly opening bottom bend, an upturned loop formed at the inner end of the top member of the inwardly opening top bend and lying in a plane therewith, said shelf engaging member being adapted to project substantially above and below the shelf and to be received between and laterally braced by the shoe boxes both above and below the shelf to which it is attached, and a shoe supporting frame carried by said member.

7. A shoe display rack formed of bent wire and comprising a shelf engaging member formed by making a reverse bend in the wire in the same plane to form an inwardly opening top bend and an outwardly bottom bend, the inner end of the inwardly opening

bend being contracted to clamp over the shelf, a link connection joining the wire at the outer end of the outwardly opening bend, an upturned loop formed at the inner end 5 of the top member of the inwardly opening loop and lying in a vertical plane therewith, and a shoe supporting frame formed by bending portions of the wire to form instep

and sole supports which are disposed horizontally when the shelf engaging portion is 10 vertically disposed.

In testimony whereof I affix my signature.

ROBERT O'TOOLE.
